DESIGN FOR A DOLL

Valrie E. McMahan, Burlingame, Calif.

Application February 21, 1944, Serial No. 112,653

Term of patent 14 years

(Cl. D34—4)

To all whom it may concern:

Be it known that I, Valrie E. McMahan, a citizen of the United States, residing in the city of Burlingame, county of San Mateo, State of California, have invented a new, original, and ornamental Design for a Doll, of which the following is a specification, reference being had to the accompanying drawing, forming part thereof.

In the drawing:

Fig. 1 is a front view of a doll showing my new design; and

Fig. 2 is a back view of the same.

I claim:

The ornamental design for a doll, as shown.

VALRIE E. McMAHAN.
